UNITED STATES PATENT OFFICE.

EDWARD J. WARING, OF NEW YORK, N. Y., ASSIGNOR TO PYRENE MANUFACTURING COMPANY, A CORPORATION OF DELAWARE.

GAS-GENERATOR.

1,183,922.

Specification of Letters Patent. Patented May 23, 1916.

Application filed July 28, 1915. Serial No. 42,300.

To all whom it may concern:

Be it known that I, EDWARD J. WARING, a citizen of the United States, and resident of the city, county, and State of New York, have invented certain new and useful Improvements in Gas-Generators, of which the following is a specification.

This invention relates to a gas generator adapted for various uses where it is desired to expel a liquid from a container.

The object of this invention is to provide a gas generator in the form of a separate device which may be attached to an ordinary tank or liquid container, thus adding new functions and increasing the usefulness of the device as a whole.

One application of the device embodying the present invention is in connection with portable fire extinguishers designed to have the fire extinguishing liquid contained therein expelled by pressure.

It has been found desirable, in order to insure a sufficient liquid expelling pressure, that such pressure be created at the time when the device is to be used and the most satisfactory results have been obtained by generating a gas through the action of a reagent upon a chemical. Fire extinguishers of the type in which gas is generated by the action of the reagent upon the chemical dissolved in the extinguishing fluid itself are disadvantageous in that, in order to obtain the proper reaction, the choice of substances which may be employed in connection with the extinguishing fluid is extremely limited.

The fluid when ejected frequently contains some of the chemicals which have not been acted upon by the reagent and, also, some of the reagent (acid).

It is an object of this invention to provide a gas generator which is an entirely separate device from the receptacle for the liquid and which may be assembled and provided with the proper gas generating reagents independently of the liquid receptacle and be conveniently attached to any liquid receptacle after the latter has been filled, or detached therefrom to permit of filling of the latter, or of inspection thereof, without interfering with the gas generator.

An embodiment of the invention is illustrated in vertical section in the accompanying drawing.

In the drawing the chamber for containing the chemical to be acted upon by the re-

agent is shown at 2 and the casing thereof terminates at its upper end in a screw-threaded casting 3, upon which is screwed a cover 4 having a handle 5, the casting being screwed against a gasket 6 in the cover 4.

The bottom of the chamber 2 comprises a casting 10 having a depending screw-threaded flange 11, which is threaded to fit the top or mouth of the receptacle 12 with which it is to be used. The gas generator is detachably secured to the receptacle 12, which contains the liquid to be expelled, by screwing the flange 11 upon the upper end of the receptacle, which may be of any desired construction. The upper end of the receptacle bears against a gasket 10' in the casting 10.

Supported in the casting 10, about mid-way of its height, is a cup 13 in which rests loosely, upon the spacing lugs 14, the container 15 for the reagent (such as an acid). The cup 13 extends a short distance into the receptacle 12 and has a tube 16 attached to its lower end which extends downwardly to within a short distance from the bottom of the receptacle 12. At the top of this tube 16 is a valve passage 17 controlled by a ball valve 18, whereby passage of liquid from receptacle 12 to chamber 2 is prevented. The bottom of the generating chamber, which is formed partially by the cup 13, comprises a detachable cover or cap closing the mouth of the receptacle 12 and may replace the usual cap or cover. The container 15 is provided with a loose fitting stopper 20 and is held in position in the cup 13, when the device is inverted, by a ring 21 attached to bars 22 projecting from the under side of the cover 4, as shown in the drawing.

When it is desired to expel the contents of the receptacle 12 the device is inverted, allowing the stopper 20 to fall away from the container 15 and the contents thereof to escape into chamber 2, causing a chemical reaction producing a gas. The generated gas flows between the container 15 and the wall of the cup 13, through the valve 17-18 and tube 16, creating a pressure in the receptacle 12 which acts to force the liquid therein out through the usual hose and nozzle attachment 23-24.

It will be apparent from the above description that the gas generator forms, for

purposes of assembling, a unitary device entirely separate and removable from the liquid containing receptacle and that access may be had to the interior of the latter at 5 any time without disturbing the contents of the gas generator. Or the gas generator may be removed, cleaned and recharged with the chemicals without disturbing the contents of the liquid receptacle. A further 10 feature and advantage of this construction and arrangement of a separate and detachable gas generator is that if the contents of the receptacle are only partly expelled the gas generator may be removed 15 and another substituted, thus rendering the device instantly ready to be again used.

What I claim is:

1. A gas generator comprising a unitary and removable device adapted to be attached 20 to a liquid receptacle, said generator having a chamber with the bottom portion thereof adapted to close the mouth of said receptacle, a member extending downwardly from the bottom of the said chamber into the said 25 receptacle to provide communication therebetween, an acid container positioned in said chamber, and means for detachably securing the bottom of said gas chamber to the said receptacle.
2. A gas generator comprising a unitary and removable device adapted to be attached to a liquid receptacle, said generator having a chamber with the bottom portion thereof adapted to close the mouth of the said 35 receptacle, a cup forming part of the said bottom, a tube extending downwardly from the said cup into the said receptacle to provide communication between the receptacle and the said chamber, an acid container positioned in said cup, a removable cover for said chamber, a member positioned between said container and the cover of said chamber for holding the acid container in position, and means for detachably securing the 40 bottom of said gas chamber to the said receptacle with the tube extending downward into the latter.
3. A gas generator comprising a unitary and removable device adapted to be attached 50 to a liquid receptacle, said generator having a chamber with the bottom portion thereof adapted to close the mouth of the said receptacle, a member extending downwardly from the bottom of said chamber into the 55 said receptacle to provide communication therebetween, an acid container positioned in said chamber, a removable cover for said chamber, a device positioned between the container and the cover of the chamber for

holding the container in position, and a depending screw-threaded flange formed on the bottom of the said chamber for detachably securing the gas generator to the said receptacle.

4. A gas generator comprising a unitary 65 and removable device adapted to be attached to a liquid receptacle, said generator having a chamber with the bottom portion thereof adapted to close the mouth of the said receptacle, a cup forming a part of the bottom 70 of the said chamber, a tube extending downwardly from the said cup into the said receptacle to provide communication between the receptacle and the said chamber, an acid container positioned in said cup, a removable cover for said chamber, a device positioned between the container and the cover of said chamber for holding the container in position, and a depending screw-threaded flange formed on the bottom of the said 75 chamber for detachably securing the gas generator to the said receptacle.

5. A gas generator comprising a unitary and removable device adapted to be attached to a liquid receptacle, said generator having 80 a chamber with the bottom portion thereof adapted to close the mouth of the said receptacle, a cup carried by the bottom of said chamber and extending above and below said bottom, a tube extending downwardly from 85 said cup into the said receptacle to provide communication between the receptacle and the said chamber, an acid container positioned in said cup, a removable cover for said chamber, a member positioned between 90 said container and the cover of said chamber for holding the container in position, and a depending screw-threaded flange formed on the bottom of said chamber and surrounding the said cup for detachably securing the gas generator to the said receptacle.

6. A gas generator comprising a unitary detachable device having its bottom portion provided with means by which said generator may be attached to the exterior and close the mouth of a liquid receptacle, said bottom portion being also provided with communicating means adapted to permit the gas generated in said generator to pass into 100 said liquid receptacle, and means for generating a gas in said generator.

Signed at the city, county and State of New York, this 20th day of July, 1915.

EDWARD J. WARING.
